UNITED STATES PATENT OFFICE.

JAMES W. WALKER, OF STRUTHERS, OHIO.

LUTING MACHINE.

Application filed May 2, 1921. Serial No. 466,211.

To all whom it may concern:

Be it known that JAMES W. WALKER, citizen of the United States of America, residing at Struthers, in the county of Mahoning and State of Ohio, has invented certain new and useful Improvements in Luting Machines, of which the following is a specification.

This invention relates to a luting machine used for sealing coke oven doors, and more particularly in coke ovens of the battery type.

The principal object of this invention is to provide a machine for sealing coke oven doors in place of doing this work as is ordinarily done by tools.

With these and other objects in view the invention consists in the combination and arrangements of parts, which will be hereinafter more fully described and claimed.

Figure 1 is a side elevation of the machine, also showing a coke oven door in position for luting.

Figure 2 is a detail view.

Figure 3 is a detail view, partly in cross section.

Figure 4 is a detail view.

Figure 5 is a cross section taken on line A—A of Figure 2.

By referring to Figure 1 it will be seen that I have provided a machine 1 mounted upon wheels 2. At the right end of this machine, 1, I have provided support legs 3 and brace members 4 which support a box shaped member 5. This box shaped member 5 to contain a hopper for the mixture to be used, and if desired a water tank and a heater. The heater designed for use in cold weather in order to keep the mixture in the hopper and the water at a desired temperature. If desired, this box shaped member 5 may also contain a division used for receiving waste material to be again placed in the hopper. This box shaped member 5 is provided with an outlet 6. Hinged to this outlet 6, I have provided a spout 7 secured by means of a bolt 8. Upon the extreme left of the machine 1 there is hinged a platform 9 which may be raised by means of a drum member 10 secured to the inner legs 3 at point 11. This drum member 10 is provided with a ratchet wheel 12, and a dog 13, for holding the drum member from rotating. In order to cause the drum member 10 to revolve, I have provided a crank 14 for the purposes of illustrating, but other means

may be employed to energize said drum member 10, such as an electric motor, etc. Fastened to this drum member 10 is a rope or a cable 15, the other end of which is secured to the outer end 16 of a bracket member 17, which is secured to the platform 9 at points 18 and 19 by any desirable means.

Mounted upon the platform 9 is a U-shaped guide member 20.

This U-shaped guide member 20 is rectangular in form, having the corners slightly rounded (see Figure 4).

By referring to Figures 2 and 5 it will be seen that I have secured within this U-shaped guide member 20 a T-shaped support member 21. This T-shaped guide member 21 is provided with conveyor plates 22, which are secured to one another by means of links 23. In order to facilitate the action of these conveyer plates 22. I have provided downwardly extending arms 24, which are carried upon journals 25, which in turn secure anti-friction rollers 26. These anti-friction rollers 26 travel upon the ledges 27 formed at the base of the T-shaped support member 21.

By referring to Figure 1 it will be seen that the end 28 of the spout 7 is directly above the upper portion of the U-shaped guide member 20. The machine as shown in Figure 1 is in position for filling the space above the conveyor plates 22 with the luting material. In order to do this I have provided ropes 29 and 30, which are attached to one of the links 23 by means of an attaching member 31 (see Figure 2). The ends of said ropes 29 and 30 are passed through openings 32 and 33 (see Figure 4).

By pulling the ropes 29 and 30 the conveyor plates 22 are caused to travel within the U-shaped guide member 20, thereby loading the machine. The machine 1 is now ready to be placed in front of an oven 34 so that the U-shaped guide member 20 will be moved so as to fit into the triangular periphery 35 formed by placing the coke oven door 36 in position. This action is brought about by operating the drum member 10, as above described, so that the platform 9 turns upon the hinge 37 and the U-shaped guide member 20 is raised to perpendicular position, and is then telescoped into the triangular periphery 35.

The coke oven door 36 is usually held in position before being luted by means of ordinary latches known to the art. In order

to keep this coke oven door 36 from falling outward, when the same does not fit snugly, I have provided a holding means consisting of a spring actuated arm 38 centrally located upon the platform 9. This spring actuated arm 38 coming in contact with the coke oven door 36 before the U-shaped guide member 20 is in a perpendicular position. The latches may now be removed without danger of the coke oven door 36 falling out of position. As the machine is now placed in position for sealing the coke oven door 36, the spring actuated arm 38 recedes into a pocket 39 (see Figure 3).

15 In order to seal the coke oven door 36 the operator causes the conveyor plates 22 to travel in either direction, as desired, thereby sealing the coke oven door 36. When the platform 9 is tilted back in a position for 20 re-loading, the upper end of the same rests upon a bracket 40.

It is understood that in filling the above mentioned receptacle for sealing 35, the parts 22 must travel over, or slide over the mortar which is naturally unevenly distributed so that there is a forcing down into the part 35, and a semi-oscillating movement of the parts 22, as they travel over the mortar in

the operation of pressing the same into the part 35.

What I claim is:

In a device of the class described, a machine mounted upon wheels, a box shaped member elevated upon suitable supports, an outlet from said box shaped member, a spout hinged to said outlet, a platform hinged to the opposite end of machine from said box shaped member, a rectangular U-shaped guide member secured to said platform, a T-shaped support member positioned within 40 said U-shaped guide member, conveyor plates positioned over the top of said T-shaped support members, links connecting said conveyor plates, anti-friction rollers secured to downwardly extending arms of said conveyor plates, operating ropes secured to said links, a spring controlled arm centrally located on said platform, means for tilting said platform, substantially as described for the purpose set forth.
